FEELER MECHANISM FOR LOOMS.

1,222,994.

Specification of Letters Patent. Patented Apr. 17, 1917.

Application filed October 23, 1916. Serial No. 127,044.

To all whom it may concern:

Be it known that I, ALONZO E. RHOADES, a citizen of the United States, residing at Hopedale, county of Worcester, State of Massachusetts, have invented an Improvement in Feeler Mechanism for Looms, of which the following description, in connection with the accompanying drawing, is a specification, like characters on the drawing 10 representing like parts.

This invention relates to automatic filling replenishing looms and is particularly concerned with the mechanism for detecting substantial exhaustion of filling in the running shuttle and to the means for operating the mechanism for initiating filling replenishment upon the detection of substantial exhaustion.

In this invention the detecting mechanism 20 comprises a feeler having four main elements, first, a filling impinging member which acts upon the beat up of the lay to enter the shuttle and contact with the filling on the filling carrier and which presents a comparatively large and smooth contacting end which thus prevents any injury or damage to the filling no matter how fine or delicate may be its quality, second, a carrier member movable relatively to and 25 normally retracted with respect to the filling impinging member so that under normal conditions the end of the carrier does not contact with the filling, third, a shuttle impinging member carried by the filling impinging member and so connected to the carrier member that the movement of either in one direction causes the other to move in the opposite direction, and the parts are so arranged that when the filling approaches 30 exhaustion the shuttle impinging member coming into contact with the shuttle wall will project the carrier member toward the filling carrier, fourth, a penetrating member 35 yieldingly projected from and slidably mounted in the carrier member and having a comparatively sharp pointed end adapted to penetrate the filling on the filling carrier and when the filling is substantially exhausted to come into contact with the filling carrier. When the carrier member is 40 projected by the engagement of the shuttle impinging member with the shuttle due to deplenishment or substantial exhaustion of filling the penetrating member which 45 is carried with it penetrates the remaining 50

filling and when the filling is so far exhausted that the penetrating member contacts with the filling carrier the penetrating member is retracted thereby relatively to the carrier, and this retracting movement is utilized to initiate filling replenishment. There is thus provided a feeler mechanism which during normal operation acts without injury to the filling and which upon deplenishment or substantial exhaustion of 60 the filling detects with accuracy so that movement is given to the detecting mechanism to initiate filling replenishment only when a predetermined and definite amount of filling remains on the filling carrier. 70

In this invention the mechanism employed to transmit the detecting action to the means for initiating filling replenishment is of a flexible and continuous character whereby a very slight movement in the detecting or feeling mechanism may be transmitted and utilized to initiate filling replenishment. Furthermore, this transmitting mechanism by reason of its flexible character may be installed in the loom without 75 interference with the other mechanisms of the loom without requiring special construction and in a cheap and efficient manner. Furthermore, this transmitting mechanism is not liable to get out of order and does not 80 lose in accuracy because of wear or lost motion. 85

The objects and nature of the invention thus set forth and others will appear more fully from the accompanying description 90 and drawings and will be particularly pointed out in the claims.

The drawings illustrate so much of an ordinary type of automatic filling replenishing loom as is necessary to an understanding by those skilled in the art of the present invention together with a preferred form of mechanism embodying the present invention applied thereto. 95

Figure 1 is a top plan view of a portion 100 of an automatic filling replenishing loom at the detecting end with a preferred form of mechanism embodying this invention applied thereto;

Fig. 2 is a front elevation of the main 105 parts shown in Fig. 2;

Fig. 3 is a side elevation looking toward the right in Fig. 1 of the feeler mechanism and its supporting bracket shown in Figs. 1 and 2; 110

Fig. 4 is a side elevation of the rearward end of the arm secured to the usual controller rock shaft for initiating filling replenishment, with the upper end of the weft hammer, and with the coöperating end of the transmitting mechanism shown chiefly in vertical cross section;

Fig. 5 is a transverse section taken on the line 5—5 of Fig. 1 on an enlarged scale omitting the lay and showing the filling impinging member in contact with the filling;

Fig. 6 is a view partially in transverse section of some of the parts shown in Fig. 5 with the filling carrier indicated diagrammatically and with the parts in position for indicating substantial exhaustion of filling.

The general character and operation of automatic filling replenishing looms, of the means for replenishing the filling, of the means for initiating filling replenishment, and of various mechanisms for feeling the filling on the carrier in the running shuttle and indicating substantial exhaustion are so well known and familiar to those skilled in the art that it will be unnecessary to describe in detail anything more than those parts directly concerned with the present invention.

Accordingly, in the drawings there has been illustrated but a small portion of an automatic filling replenishing loom. The breast beam 1 has extending parallel and in front the usual controller rock shaft 2 which when rocked acts to initiate filling replenishment in a well known manner. The lay 3 is shown with the shuttle 4 boxed at the detecting side of the loom.

The feeler or detecting mechanism is a self-contained structure bolted or otherwise secured to the flange 5 extending laterally from the loom frame. This mechanism comprises a vertical bracket 6 having a rearwardly projecting lower end 7 provided with a transverse bearing 8.

A vertical arm 9 is journaled at its lower end through the medium of the stub shaft or pin 10 in the bearing 8.

At its upper end which is extended horizontally to form a base or support 11 the arm 9 carries the filling impinging member 12 which is secured thereto by set screws 13.

This filling impinging member presents a smooth end herein shown in two parts 14 of comparatively large area. The end of the filling impinging member is located in line with the axis of the filling carrier 15 in the shuttle and a suitable slot is provided in the shuttle binder 16 and in the wall of the shuttle 4, the slot 17 in the shuttle wall being shown in Fig. 5, so that when the lay beats up the filling impinging member enters the shuttle and contacts with the filling on the filling carrier. This occurs at each beat up that the shuttle is at the detecting side of the loom, but by reason of the smooth large

surfaces of the filling impinging member no harm is done to the filling no matter how fine and delicate it may be in quality.

A rod 18 is pivoted at 19 in a lug 20 projecting forwardly from the upper end of the arm 9. At its forward end this arm 18 rides in an aperture in an arm 21 projecting forwardly and upwardly from and bolted to the bracket 6 by the bolt 22. A helical spring 23 surrounds the rod 18, abuts a shoulder 24 on the rod 18 at one end and the arm 21 at the opposite end. A stop lug 25 projects rearwardly from the bracket 6 and extends in the rear of the arm 9. It will thus be seen that the spring 23 acts to hold the arm 9 and the feeler parts supported by it in rearward position against the stop lug 25 and in the position shown in Fig. 3, while when upon the beat up the filling on the filling carrier comes into contact with the feeler the spring 23 will yield allowing the arm 9 to swing forwardly with the lay.

The carrier member or carrier 26 is shown as a wide flat plate mounted in a recess extending longitudinally of the filling impinging member and slidable longitudinally relatively thereof. A pair of levers 27 are fulcrumed on a shaft 28 extending transversely above the carrier and journaled in ears 29 projecting upwardly from and at each side of the filling impinging member. At their lower ends these levers extend through slots in the filling impinging member and are slotted to engage pins 30 projecting laterally from the carrier 26. At their upper ends the levers 27 are connected by a bearing member 31 journaled at its ends 32 in the levers. This bearing member has threaded therethrough parallel with the carrier the shuttle impinging member 33. A lock nut 34 on the threaded shank of the shuttle impinging member 33 abuts against the bearing member 31. At its forward end the shuttle impinging member 33 is extended through an aperture in the lug 35 projecting upwardly from the arm 9 and a helical spring 36 surrounds the shank and abuts at one end against a shoulder 37 thereon and at the other end against the lug 35. It will thus be seen that through the medium of the spring 36, the shuttle impinging member, and its connection with the carrier, that the carrier is normally retracted with respect to the filling impinging member so that the parts occupy the position shown in Fig. 5.

The penetrating member of the feeler is shown as a small plunger 38 mounted in a circular bore in the carrier and formed at its rear end with the penetrating conical point 39. A cross pin 40 passing through a slot 41 in the plunger 38 is secured to the carrier 26. This construction is so arranged as to allow the plunger to move forwardly in the carrier and limit its rearward projec-

tion so that the penetrating point 39 extends just beyond the rearward face of the carrier. A helical spring 42 mounted in the bore of the carrier abuts the plunger 38 at one end 5 and at the other end a hollow screw plug 43 threaded into the bore of the carrier. Thus the penetrating member is yieldingly projected from and slidably mounted in the carrier.

10 The operation of the detecting mechanism will now be apparent.

Under normal conditions the parts will occupy the position shown in Fig. 5 and as the lay beats up the mass of filling on the 15 filling carrier will come into contact with the smooth large ends of the filling impinging member and carry the arm 9 backwardly against the spring 23. As the filling is gradually unwound from the filling carrier 20 and the point is reached where but a small amount of filling remains upon the filling carrier the shuttle impinging member 33 will come into contact with the wall of the shuttle. The point at which this shall occur is 25 determined with great accuracy by the adjustment of the shuttle impinging member 33 in the threaded bearing member 31. Up to this time the carrier 26 has remained retracted with respect to the filling impinging 30 member by reason of the action of the spring 36 so that the penetrating point 39 has not come in contact with the filling and there has been therefore no tendency to mar, injure, damage or cut the filling. When, however, 35 the shuttle impinging member 33 comes into contact with the wall of the shuttle the carrier is projected rearwardly and the penetrating point 39 penetrates the filling. When upon the recurrence of this operation the remaining filling has reached a predetermined stage of exhaustion the penetrating point will come into contact with the surface of the filling carrier itself and will be retracted thereby against the action 40 of the spring 42. This movement of the penetrating member is the one which is utilized to effect initiation of filling replenishment.

Necessarily the movement given to the 50 penetrating member is slight and this slight movement must be immediately and effectively transmitted to the filling replenishing mechanism. This result is secured by the present invention.

55 In the construction illustrated the controller rock shaft 2 operates the arm 44 extending upwardly and rearwardly over the breast beam. This arm carries at its rearward end and projecting rearwardly a dog 45 pivoted transversely of the arm at 46. A bunter herein shown as the usual weft hammer 47 swings forwardly and rearwardly beneath the dog 45, the rear end of which is maintained elevated just above the path of the bunter by a helical spring 48 mounted in

the socket 49 and abutting the forward end of the dog.

A flexible sheath herein shown as a wire helix 50 is secured at one end in the bore of the screw plug 43 and at its opposite end in a split plug 51 clamped by a set screw 52 in a vertical aperture in a bracket 53 bolted at 54 to the rear face of the breast beam so that the end of the sheath is directly beneath the forward end of the dog 45. A flexible core herein shown as a wire 55 extends through the helix. At one end it abuts a pin 56 forming a continuation of the plunger 38 and at the other end it is provided with a head or plunger 57 in contact with the forward end of the dog 45.

70 The sheath and the core present a flexible connection comprising two relatively and longitudinally movable substantially continuous juxtaposed parts one of which acts to support the other and it will be apparent that the function may be secured without the particular construction illustrated being employed for these parts.

75 This flexible connection insures the slight movement of the penetrating member being transmitted positively and accurately to the dog 45 so that when the penetrating member is retracted upon the occurrence of filling exhaustion to the required degree the dog 45 is swung about its pivot to bring its rearward end into the path of the bunter 47, and immediately the shaft 2 is rocked to initiate the action of the filling replenishing mechanism.

80 Having fully described my invention, what I claim as new and desire to secure by Letters Patent is:

1. In an automatic filling replenishing loom the combination of a shuttle containing a filling carrier; a filling impinging member acting upon the beat up to enter the shuttle and contact with the filling on the filling carrier; a carrier movable relatively to, and normally retracted with respect to, 105 said filling impinging member; a shuttle impinging member carried by said filling impinging member and connected to said carrier to move reversely therewith; and a penetrating member yieldingly projected from, and slidably mounted in, said carrier and adapted, when the carrier is projected by the engagement of the shuttle impinging member with the shuttle due to deplenishment of filling, to penetrate the remaining 110 filling and, upon contact with the filling carrier, to be retracted thereby relatively to the carrier.

115 2. In an automatic filling replenishing loom the combination of a shuttle containing a filling carrier; a filling impinging member acting upon the beat up to enter the shuttle and contact with the filling on the filling carrier; a carrier movable relatively to, and normally retracted with re- 120 125 130

spect to, said filling impinging member; a shuttle impinging member carried by said filling impinging member and connected to said carrier to move reversely therewith; a 5 penetrating member yieldingly projected from, and slidably mounted in, said carrier and adapted, when the carrier is projected by the engagement of the shuttle impinging member with the shuttle due to deplen-
 10 ishment of filling, to penetrate the remaining filling and, upon contact with the filling carrier, to be retracted thereby relatively to the carrier; and means operated by said re-
 15 traction of said penetrating member to initiate filling replenishment.

3. In an automatic filling replenishing loom, the combination of a shuttle containing a filling carrier; a filling impinging member acting upon the beat up to enter 20 the shuttle and contact with the filling on the filling carrier; a carrier movable relatively to, and normally retracted with respect to, said filling impinging member; a shuttle impinging member carried by said 25 filling impinging member and connected to said carrier to move reversely therewith; a penetrating member yieldingly projected from, and slidably mounted in, said carrier and adapted, when the carrier is projected 30 by the engagement of the shuttle impinging member with the shuttle due to deplen-
 35 ishment of filling, to penetrate the remaining filling and, upon contact with the filling carrier, to be retracted thereby relatively to the carrier; means for initiating the operation of filling replenishing means; and a flexible connector extending between said penetrating member and said initiating means and comprising two relatively and longitudinally 40 movable substantially conterminous juxtaposed parts one of which acts to support the other, the penetrating member when retracted acting to give relative longitudinal movement to said connector parts and there-
 45 through and thereby to set in operation the said initiating means.

4. An automatic filling replenishing loom comprising means for initiating the operation of filling replenishing mechanism; a

member moved upon the deplenishment of filling to a predetermined extent in the running shuttle; and a flexible connector extending between said initiating means and said member and comprising two relatively and longitudinally movable substantially conterminous juxtaposed parts one of which 55 acts to support the other, the said member acting when moved to give relative longitudinal movement to said parts and there-
 60 through and thereby to set in operation the said initiating means.

5. An automatic filling replenishing loom comprising means for initiating the operation of filling replenishing mechanism; a member moved upon the deplenishment of filling to a predetermined extent in the running shuttle; a flexible sheath having its ends secured against longitudinal movement, one adjacent the said member and the other adjacent the said initiating means; a flexible 65 core located in and longitudinally movable with respect to said sheath; and means operated by the movement of the said member to transmit longitudinal movement to said core and therefrom to said initiating means to 70 initiate the operation of the filling replenishing mechanism.

6. An automatic filling replenishing loom comprising a self-contained feeler detecting mechanism, a bracket for supporting the same, means for securing the bracket to the loom frame, means for initiating the operation of filling replenishing mechanism, and a flexible connector extending between said initiating means and said detecting means 75 and comprising two relatively and longitudinally movable substantially conterminous juxtaposed parts, one of which acts to support the other, the said detecting means acting when operated by substantial exhaustion 80 of filling to give relative longitudinal movement to said parts, and therethrough and thereby to set in operation the said initiating means.

In testimony whereof, I have signed my name to this specification.

ALONZO E. RHOADES.
